NASAL MEDICINE DROPPER OR THE LIKE

Donald E. Hill and Fern B. Hill, Burbank, Calif.

Application April 28, 1958, Serial No. 50,635

Term of patent 14 years

(Cl. D83—1)

Fig. 1

Fig. 2

Fig. 3

Fig. 4

Fig. 1 is a top plan view of a nasal medicine dropper or the like, showing our new design;

Fig. 2 is a front elevational view thereof, the rear being substantially plain;

Fig. 3 is a side elevational view, both sides being identical; and

Fig. 4 is a bottom plan view thereof.

We claim:

The ornamental design for a nasal medicine dropper or the like, substantially as shown and described.
